UNITED STATES PATENT OFFICE.

WILLIAM WALLACE HESSON, OF TORONTO, ONTARIO, CANADA, ASSIGNOR TO ALBERT FREEMAN, OF NEW YORK, N. Y.

TOBACCO PIPE.

Application filed April 16, 1925. Serial No. 23,709.

To all whom it may concern:

Be it known that I, WILLIAM WALLACE HESSON, a subject of the King of Great Britain, and resident of the city of Toronto, 5 county of York, Province of Ontario, in the Dominion of Canada, have invented certain new and useful Improvements in Tobacco Pipes, as described in the following specification and illustrated in the accompanying 10 drawings, that form part of the same.

The principal objects of the invention are to eliminate many of the disagreeable features incident to smoking, and to provide a 15 pipe, cigar or cigarette holder which may be kept in a thoroughly sanitary condition.

The principal features of the invention consist in the novel construction and arrangement of an extension stem from the mouth-piece which will maintain a thoroughly tight joint between the stem and the bowl so that moisture cannot get around the exterior of the stem and a clear passage 20 will be maintained from the bowl to the mouth-piece.

25 In the accompanying drawings, Figure 1 is a sectional perspective view of a pipe showing one form of my improved extension stem.

Figure 2 is a similar view showing a 30 slight modification of structure.

Figure 3 is a similar sectional view showing a further modification of the metal stem.

Figure 4 shows a still further modified 35 structure.

The most undesirable feature about pipe smoking or the use of cigar or cigarette holders is that moisture, ashes and tobacco collect in pockets in the stem between the 40 mouth-piece and the bowl and such collections are extremely undesirable.

Pipes having metallic tubular stems of 45 various forms have been devised, but the present invention contemplates maintaining a continuous passage from the bowl to the mouth-piece without pockets and in which leakage of moisture from the bowl around the stem will be absolutely avoided.

The invention may be applied in various 50 forms. In the construction illustrated in Figure 1, the bowl shank or stem 1 is bored longitudinally with an orifice 2 which terminates in a shoulder 3 arranged close to the bowl 4.

55 A small opening 5 of a suitable size to

allow the smoke to pass therethrough is arranged in central alignment with the orifice 2.

The outer end 6 of the orifice 2 is threaded with a thread of greater diameter than the orifice 2. The mouth-piece 7 is bored longitudinally to receive the metal tube 8 which is provided with a threaded portion 9, half of which threads into the correspondingly threaded portion of the mouth-piece 7 65 and the other half of which threads into the threaded portion 6 of the bowl stem 1.

The tube 8 extends beyond the threaded portion 6 and is provided with an enlarged end 10 of substantially the same diameter as 70 the orifice 2, and this enlarged portion is provided with a squared end 11 adapted to snugly abut the shoulder 3 in the pipe stem.

The metal stem 8 is cemented or otherwise rigidly secured in the mouth-piece 7 and the 75 threaded portion 9 of the tube extending beyond the mouth-piece enters the threaded portion of the pipe stem or shank and secures the mouth-piece firmly in position and completes a passage from the bowl to the 80 end of the mouth-piece having no lateral pockets in which moisture may collect.

The metallic stem is made in a very simple manner and accomplishes a very desirable condition in the pipe.

In the form illustrated in Figure 2 the metal stem 12 extends beyond the inner end of the mouth-piece and is provided with a threaded portion 13 adjacent to the cylindrical end portion 14. The threaded portion 90 engages the inner threaded wall of the pipe stem and the end portion 14 is drawn tightly against the shoulder 3.

In the form illustrated in Figure 3 the metal stem 15 fits snugly in the bore 16 of 95 the pipe stem and has an enlarged portion 17 which is preferably provided with a tapered end 18. This enlarged portion fits into the outer end of the stem of the bowl. This particular form may be made very 100 economically by having the portion 17 made in the form of a ferrule to slip over the reduced threaded end 19 which threads into the mouth-piece 20 and is permanently cemented therein.

In Figure 4 a structure very similar to that shown in Figure 3 is shown but the tubular stem 21 has an enlarged inner end portion 22 which abuts a gasket or washer 23 of a soft material, such as cork or leath-

er and forms therewith a moisture tight joint.

The tube 21 is provided with a threaded portion 24 which is screwed into the mouthpiece 25.

A pipe such as described may be kept very clean and in a sanitary condition as the inner stem abuts tightly against the shoulder in the bowl shank and said shoulder is 10 very close to the interior wall of the bowl.

Leakage of vapor or moisture around the end of the metal tube 8 is prevented by the tight joint at the shoulder 3 and hence the shank of the bowl is kept dry and accumulation 15 of the filth therein is prevented. In ordinary pipes, due to the absorbent nature of the wood, the shanks of the bowls become saturated to such an extent that it is impossible to cleanse them, generally rendering 20 them unfit for use, while one of my pipes may be used and enjoyed indefinitely.

What I claim as my invention is:—

1. A tobacco pipe comprising a bowl having an integral shank or stem and a mouthpiece, the shank having an enlarged counter-bore extending from its outer end entirely through the shank and terminating in a flat annular shoulder close to the interior wall of the bowl and a short perforation 25 connecting said counter-bore with the interior of the bowl, the mouthpiece having a longitudinal perforation and a counter-bore opening at its inner end, and a tubular mem-

ber permanently secured in the counter-bore of the mouthpiece and fitted into the shank 35 and having a squared end abutting and fitting said annular shoulder to prevent leakage when the parts are assembled, whereby a continuous passage without lateral pockets is formed leading from the interior of 40 the bowl through the mouthpiece, and contamination of the shank of the bowl is avoided.

2. A tobacco pipe comprising a bowl having an integral shank or stem and a mouthpiece, the shank having an enlarged counter-bore extending from its outer end, entirely through the shank, and terminating in a flat annular shoulder close to the interior wall of the bowl and a short perforation 45 connecting said counter-bore with the interior of the bowl, the mouthpiece having a longitudinal perforation and a counter-bore opening at its inner end, and a tubular member permanently secured in the counter-bore of the mouthpiece and screw-threaded 50 into the shank and having a squared end abutting and fitting said annular shoulder to prevent leakage when the parts are assembled, whereby a continuous passage without lateral pockets is formed leading from the interior of the bowl through the mouthpiece; and contamination of the shank of the bowl is avoided.

WILLIAM WALLACE HESSON.
